UNITED STATES PATENT OFFICE.

CHARLES A. MCINTYRE, OF PHILADELPHIA, PENNSYLVANIA.

ELEVATOR-SIGNAL.

1,121,649.

Specification of Letters Patent. Patented Dec. 22, 1914.

Application filed June 11, 1913. Serial No. 773,013.

To all whom it may concern:

Be it known that I, CHARLES A. MCINTYRE, a citizen of the United States, residing at Philadelphia, in the county of Philadelphia and the State of Pennsylvania, have invented new and useful Improvements in Elevator-Signals, of which the following is a specification.

My invention relates to new and useful improvements in elevator signals, and has for its object to provide an exceedingly simple and effective device of this character, whereby the operator of the elevator will be notified by suitable signals, such as lights, in advance of the floor at which he is to stop, and again just before reaching the stopping place.

A further object of the invention is to provide an elevator signal whereby the waiting prospective passenger will be notified by suitable signals of the approach of the elevator, say one floor in advance, and again when the elevator reaches the floor on which the person is waiting.

A still further object of the invention is to provide a plurality of ramps arranged in series and located in the elevator shaft in any convenient position, said ramps being electrically connected with different objects, such as signals and magnets.

Another object of the invention is to situate a track adjacent the ramps on which runs a traveler carrying contact member arranged in series and adapted to close the circuits at certain times, said traveler being operated by the movement of the elevator either directly or indirectly.

Still another object of the invention is to provide means operated by the opening of the elevator shaft door to close the circuit through the magnets thereby energizing said magnets, and causing them to break the circuit through the signals previously made.

A further object of the invention is to provide the traveler with two sets of pivoted contact members, one set of which is caused to co-act with certain ramps, when the elevator is ascending, while the other set is caused to co-act with certain other ramps when the elevator is descending the first named set then being removed from their co-operating set of ramps.

With these ends in view, this invention consists in the details of construction and combination of elements hereinafter set forth, and then specifically designated by the claims.

In order that those skilled in the art to which this invention appertains may understand how to make and use the same, I will describe its construction in detail, referring by numerals to the accompanying drawing forming a part of this application, in which—

Figure 1, is a vertical sectional view of an elevator shaft, diagrammatically illustrating the wiring of my improved elevator signal. Fig. 2, is a similar view of a slightly modified form of my invention, Fig. 3, is an enlarged diagrammatical view of the ramps, traveler and wires shown in the upper portion of Fig. 1. Fig. 4, is a side elevation of the traveler, and its cooperating parts. Fig. 5, is a face view thereof, at right angle to Fig. 4, and Fig. 6, is an end view thereof.

In carrying out my invention as illustrated in Figs. 1 and 3, the elevator shaft is represented by the numeral 2, having a door 3 at each floor which is hung in the ordinary manner, and provided with a cam bracket 4, 80 for a purpose to be hereinafter described. Within the elevator shaft is situated the elevator car 5, provided with the ordinary cable 6, one end of which carries the counterbalancing weight 7, said cable running over the ordinary sheave 8, which is mounted at the top of the elevator shaft. Power is transmitted from this sheave through its shaft 9, the pulley 10 thereon, the belt 11, and pulley 12 to the shaft 13 on which the last 90 named pulley is mounted. The shaft 12 and a similar shaft 14 are each provided with a groove pulley 15, on which are spirally wound the rope or cable 16, each end of said cable having attached thereto a weight 17. 95 Said cable 16 is attached to the traveler 18, whereby motion is transmitted from the shaft 13 to said traveler, the weights 17 holding the cable 16 taut.

The traveler 18 shown in Figs. 4, 6 inclusive comprises a slide 19, which straddles the track 20, snugly fitting the latter in order to provide a necessary amount of friction between the two. The slide 19 is pro-

vided with 4 pins or stoppers, 21, 22, 23 and 24. 25 denotes an arm to which is attached the cable 16, and one end of said arm is bifurcated, so as to pass around the track 20 and the slide 19, and a portion of said bifurcated end is bent to lie at an angle to the body of the arm, thereby producing a pair of extensions 26 and 27. To each of these extensions is pivoted a set of bell 10 crank levers, 28, 29, 30, 31, 32 and 33, one set adapted to be used when the elevator is ascending, and the other set when the elevator is descending, and these bell crank levers are properly insulated from each 15 other, and from the extensions 26 and 27, by suitable insulating material 34, in the form of sleeves, which surround the pivot members 35. The toe end of each bell crank lever carries a contact shoe 36, adapted to 20 coöperate with the different ramps, 37, 38, 39, 40, 41, 42, 43, 44, 45, 46, 47, 48, 49, 50, 51, 52, 53, 54, 55, 56, 57, 58, 59, 60, while the opposite ends project into the spaces between the pins 21 and 22 and 23 and 24, and 25 when said bell crank levers contact with said pins, the contact shoes 36 are caused to engage or disengage the ramps, depending upon the direction in which the traveler is moved. In order to prevent the bell crank 30 levers from being moved too far out of engagement with the ramps, I provide pins 61 and 62, one of which is carried by each of the extensions 26 and 27, and against which will rest the bell crank levers when 35 they are moved in the direction which will disengage the contact shoes from the ramps. The arm 25 and the slide 19 are kept in their relative positions by the strap 63, which is carried by the arm 25, said strap being provided 40 with a slot 64, through which passes a retaining bolt or stud 65, the latter being secured to the slide 19.

The action of the traveler is as follows: Referring to Figs. 4 and 5, when the traveler is moved to the right, the bell crank levers 28 to 30 inclusive will be brought into engagement with the pin 22, causing the contact shoes thereof, to engage the ramps, and this action of the traveler will bring the 45 bell crank levers 31 to 33 inclusive into contact with the pin 24, thereby causing their contact shoes to be disengaged from the ramps. When the traveler is moved in the opposite direction or toward, the left, of 50 the slide 19, because of the friction between it and the track 20, will stand still and allow the bell crank levers 28 to 30 inclusive, to engage the pin 21, causing their contact shoes to be disengaged from the ramps, and 55 the same action will cause the bell crank levers 31 to 33 inclusive to engage the pin 23, thus forcing their contact shoes into engagement with the ramps.

It will be noticed that the contact shoes

are placed in and out of engagement with the ramps by the action of the pins 21 to 24 inclusive upon the bell crank levers, and as the pins of each pair are some distance apart, the elevator could "drift" some distance without changing the relation between the different contact shoes and the ramps.

The bell crank levers 30 and 33 have attached thereto, a common wire 66 leading to the source of electrical energy 67. The bell crank levers 29 and 32 are connected by a common wire 68, which passes through the flexible conductor 69, to the signal 70, which is preferably in the form of an electrical light bulb, and will be termed for convenience the "floor" signal. The bell crank levers 28 and 31 are connected by a common wire 71, which also passes through the flexible conductor, and this wire is attached to the signal 72, in the form of an electrical light bulb, and for convenience will be termed the advance signal. The signals 70 and 72 are connected with the wire 66, which leads to the source of electrical energy by a wire 73, which is common to both of said signals.

Adjacent the doors of the elevator shaft are situated signals 74, 75, 76, 77, 78, and 79, preferably in the form of electric light bulbs, and it will be noted that only one of these signals is provided for the first and top floors, while the intermediate floors each have 2 of such signals. The signal 74 is connected by a wire 80 and its branches with the ramps 41, 38 and 53 and by a wire 81 with the contact point 82. The signal 75 is connected by a wire 83 and its branches with the ramps 39 and 42, and also by a wire 84 with the contact point 85. The signal 76 is connected by a wire 86 and its branches with the ramps 37, 54, 57 and also by a wire 87 with the contact point 88. The signal 77 is connected by a wire 89 and its branches with the ramps 40, 43 and 60, and by a wire 90 with the contact point 91. The signal 78 is connected by a wire and its branches 92 with the ramps 55, 58 and also by a wire 93 with the contact point 94. The signal 79 is connected by a wire 95 and its branches with the ramps 44, 56 and 59, and by a wire 96 with the contact point 97.

The contact points 82, 85, 88, 91, 94 and 97 are engaged by the plunger switches 98, 99, 100, 101, 102, 103 respectively, whenever a person signals the elevator operator, thereby partially closing the circuit through the line wire 104 to which said switches are connected, said line wire leading to the source of electrical energy 67. In order that said plunger switches may be disengaged from their respective contact members, when the elevator stops at a floor, and the door of the elevator shaft is open, I provide magnets 105, 106, 107, 108, 109, 110, one of which is adjacent each of the plunger switches,

said magnets adapted to act upon said switches for disengaging them from their contact points, when said magnets are energized. The magnet 105 is connected by a 5 wire 111 and its branches, with the ramps 45 and 49. The magnet 106 is connected by a wire 112, with the ramp 46. The magnet 107 is connected by a wire 113 with the ramp 50. The magnet 108 is connected by a 10 wire 114 with the ramp 47. The magnet 109 is connected by a wire 115 with the ramp 51. The magnet 110 is connected by a wire 116 and its branches to the ramps 48 and 52. After the circuit through the magnets have 15 been partially closed by the contact shoes engaging the "magnet" ramps, said circuits are completed by the opening of the elevator shaft doors, because the cam brackets carried by said doors will operate the levers 20 117, one of which is mounted adjacent each door, and carried by the shaft 118, running across all of the doors of the different elevator shafts, when they are built in "banks". On the shaft 118 is mounted a 25 single connector 130, to which is pivoted a rod 119 which carries one or more contact members 120, said contact members co-acting with the magnets for completing the circuit through the line wire 104, to which each of 30 the contact members 120 is connected.

The operation of the device is as follows: Presuming that a person standing on the third floor wishes to use the elevator which is descending, and the plunger switch 100 35 has been pressed inward, causing it to co-act with the contact point 88, thereby partially completing the circuit. As soon as the elevator has descended to a point where the contact shoe of the bell crank lever 32 will 40 come in contact with the ramp 54, which is for the floor light in the descending set of ramps, said circuit will be entirely completed through the source of electrical current 67, a portion of the wire 66, the wire 73, 45 the floor signal 70 in the elevator, the wire 68, the bell crank lever 32 and its contact shoe, the ramp 54, the branches of the wire 86 leading to said ramp, said wire 86, the descending signal 76 on the third floor, the 50 wire 87 to the contact point 88, then through the plunger switch 100, and the line wire 104, to the source of electrical energy 67, thus operating the signals 70 and 76 to indicate to the elevator operator that he is to 55 stop at the third floor, and also indicating to the waiting person that the elevator has reached the third floor. The elevator having reached the third floor, it has also caused the contact shoe of the bell crank lever 33 to 60 coact with the ramp 50, partially completing a second circuit, and as soon as any one of the elevator shaft doors on the third floor is opened, one of the levers 117 will be operated by the cam bracket 4, and cause one

of the contact members 120 to engage the magnet 107, thus completing the circuit through the source of electrical energy 67, the wire 66, the bell crank lever 33 and its contact shoe, the ramp 50, the wire 113, the magnet 107, its contact 120 and the line wire 104 to the source of electrical energy 67, thereby energizing said magnet 107, causing it to return the plunger switch 100 to its normal open position, and thereby breaking the first named circuit, causing the signal 75 lights to be extinguished. The position of the elevator at the third floor has also caused a third circuit to be partially closed by the co-operation of the contact shoe of the bell crank lever 31 with the ramp 58, and if a 80 person waiting upon the second floor has closed the "down" plunger switch 102, then a circuit will be completed through the source of electrical energy 67, a portion of the wire 66, the wire 73, the advance signal 85 72, the wire 71, the bell crank lever 31 and its contact shoe, the ramp 58, the branch of the wire 92 leading from said ramp, said wire 92, the descending signal 78 on the second floor, the wire 93, the contact 94, the 90 plunger switch 102 and the line wire 104 to the source of electrical energy 67, thus causing the signals 72 and 78 to be operated, indicating to the operator of the elevator that he is to stop at the next or advance floor, 95 and also indicating to the waiting person that the elevator is approaching. This same operation takes place at any, and all floors. It is to be understood that the same signal light on the floor indicates when the elevator 100 is approaching, and when it reaches the floor. When the elevator is ascending, the contact shoes of the bell crank levers 31 to 33 inclusive, will be disengaged from their ramps, as hereinbefore described, and the contact shoes of the bell crank levers 28 to 30 inclusive will be caused to engage their respective ramps, which is the ascending set, so that the different signals may be given in 105 the same manner as hereinbefore described, except that the circuit will be completed through other wires, and the upward indicating signals or lamps on the different floors. When a person standing on the top floor signals for the elevator, and said elevator is ascending, a signal will be shown in the advance light 72 in the elevator, when the latter reaches the next to the top floor, here shown as the third floor, and will also 110 show a signal on the top or fourth floor by the light 74, because the contact shoe of the bell crank lever 28 is in contact with the ramp 38, and as the elevator ascends to the top or fourth floor the signal lamp 74 115 will indicate that the elevator is at that floor, because the contact shoe of the bell crank lever 29 will then be in contact with the ramp 41. The ramps 45 and 49 being 120 125

connected with the magnet 105, no matter what direction the elevator is traveling prior to stopping at the 4th or top floor, when the door is opened, the magnet will be energized for breaking the circuit through the signals.

In Fig. 2, I have shown a slightly modified form of my invention in which the ramps are situated longitudinal of the elevator shaft, and the different ramps are located adjacent the floors, so that the circuits are completed at the floor which the elevator is to stop at, and again at the floor in advance to that floor at which the elevator is to stop. These ramps are similar to those hereinbefore described, except that they would be of greater length, since that contact shoes of the bell crank levers must travel a greater distance for the traveler to which said bell crank levers are pivoted is attached directly to the elevator. In this form of the invention the ramps will be numbered, the same as first used in my preferred form, and the wires running from said ramps to the signals on the floors of the building will also contain the same numbers as hereinbefore used for such wires, the only difference being in the numbering of the wires running from the flexible conductor 69, which in this case contains only the wire 73. The wire 73 is connected with a rosette 121 in the elevator and from this rosette leads a wire 122 to the bell crank levers 30 and 33, while a second wire 123 leads from the rosette to the signal 70 in the elevator, and from said signal another wire 124 leads to the bell crank levers 29 and 32, and still another wire 125 leads from the rosette to the signal 72 in the elevator, which is connected by a wire and its branch 126 with the bell crank levers 28 and 31, so that the different circuits may be completed as hereinbefore described for my preferred form.

Of course I do not wish to be limited to the exact details of construction as here shown, as these may be varied within the limits of the appended claims without departing from the spirit of my invention.

Having thus fully described my invention, what I claim as new and useful, is—

1. The combination with an elevator car, its actuating mechanism, two sets of signaling devices, one for ascending and descending cars, located outside of the elevator shaft and a "floor" and "advance" signals located within the car, of a plurality of ramps located within the shaft, forming a portion of the signaling circuits insulated from each other and from the ground, said ramps being divided into a descending set and an ascending set, a traveler operated by the elevator car, and comprising a slide an arm coupled to said slide, and movably independent of said slide within certain lim-

its, bell crank levers pivoted to said arm, 65 said bell crank levers being divided into 2 sets, contact shoes carried by said bell crank levers, adapted to co-act with the several ramps for partially completing the signaling circuits, and means carried by the slide 70 for contacting with the bell crank levers to cause one set of contact shoes to be disengaged from their ramps and simultaneously cause the other set of contact shoes to engage their respective ramps. 75

2. In a device of the character stated the combination with a plurality of ramps located within an elevator shaft, of a track adjacent said ramps, a traveler operated by an elevator car and comprising a slide arranged to straddle the track and frictionally engaging the latter, a bifurcated arm, a strap carried by said arm, means carried by the slide and engaging the strap for holding the bifurcated arm and slide in their relative positions, two sets of bell crank levers carried by the bifurcated arm, contact shoes carried by said bell crank levers, means carried by the slide arranged to be engaged by the bell crank levers at certain predetermined times to disengage one set of contact shoes from their respective ramps and cause the other set of contact shoes to engage their respective ramps, and means for limiting the movements of the bell crank levers. 95

3. In a device of the character stated the combination with a plurality of ramps located within an elevator shaft, of a track adjacent said ramps, a traveler operated by an elevator car and comprising a slide arranged to straddle the track and frictionally engaging the latter, a bifurcated arm, a strap carried by said arm, means carried by the slide and engaging the strap for holding the bifurcated arm and slide in their relative positions, two sets of bell crank levers pivoted to the bifurcated arm, one set on each side thereof, said bell crank levers provided with outwardly projecting arms, contact shoes carried by the inner ends of said bell crank levers, and pins carried by the slide, one of said pins being situated on each side of the arms of each set of bell crank levers whereby the movement 115 of the bifurcated arm will cause the bell crank lever arms to contact with certain of said pins to cause one set of contact shoes to engage their respective ramps and the other set of contact shoes to be disengaged 120 from their respective ramps for the purpose specified.

4. In a device of the character stated the combination with a track and a plurality of ramps on each side thereof, of a slide frictionally engaging the track, a bifurcated arm loosely connected to the slide and having a limited movement with relation to

said slide, pins carried by the slide and bell crank levers pivoted to the bifurcated arm, and so arranged that when the bifurcated arm is moved with relation to the slide, one set of said bell crank levers will be disengaged from their respective ramps, and the other set of bell crank levers will be engaged with their respective ramps.

In testimony whereof, I have hereunto affixed my signature in the presence of two 10 subscribing witnesses.

CHARLES A. McINTYRE.
